UNITED STATES PATENT OFFICE.

HENRY MUELLER, OF DECATUR, ILLINOIS, ASSIGNOR TO H. MUELLER MANUFACTURING COMPANY, OF DECATUR, ILLINOIS, A CORPORATION OF ILLINOIS.

WATER-STRAINER.

No. 908,308.

Specification of Letters Patent.

Patented Dec. 29, 1908.

Application filed November 7, 1907, Serial No. 401,092. Renewed July 25, 1908. Serial No. 445,343.

To all whom it may concern:

Be it known that I, HENRY MUELLER, a citizen of the United States, and resident of Decatur, Macon county, State of Illinois, have invented certain new and useful Improvements in Water-Strainers; and my preferred manner of carrying out the invention is set forth in the following full, clear, and exact description, terminating with claims 10 particularly specifying the novelty.

This invention relates to water purification, and more especially to that class of devices known as filters of the strainer type; and the object of the same is to produce improvements in a strainer of this character.

To this end the invention consists in a peculiar shaped strainer which provides a large working surface in comparatively small space so as not to retard the flow of the liquid even 15 under excessive pressure.

The invention also consists in the provision of a distinct sediment chamber below the strainer, a baffle plate directing the inflowing liquid into this chamber, and other 20 details of construction as will appear below.

In the drawings Figure 1 is a central longitudinal vertical section through this device complete; Fig. 2 is a plan view of the strainer and spider; and Fig. 3 is a side elevation of 25 the strainer alone.

Referring to the accompanying drawings which form part of this specification and in which the same reference numerals are used on corresponding parts in the several views, 30 1 designates the casing or body which is by preference a hollow casting shaped about as shown and having flanges 20 around the openings at its upper and lower ends and flanges 20^a around the openings at its sides.

40 The top and bottom openings are provided with suitable closures of which two different types are illustrated in Fig. 1. That for the top is here shown as a flat cap 15 bolted to the flange 20 with packing 11 between them, 45 and preferably having an annular rib 13 on its inner face which centers it accurately over the opening. That for the bottom may be an extension, and as here shown is a reducer 15^a, with the same packing 11 and rib 50 13; and a flat cap 9 is also here shown as closing the reducer in the same way that the cap 15 closes the top, except that the cap has a central plug 10. Obviously either form of closure could be employed, but the arrange-

ment illustrated is probably the most serv- 55 iceable.

The numerals 14 designate pipes, that marked A being the inlet bolted to the flange 20^a at the inlet side 16 of the body, and that B being the outlet at the outlet side 16^a of 60 the body. However, I do not wish to be confined to this exact manner of connecting the pipes with the strainer, as it forms no part of the present invention.

The upright casing 1 of the strainer is cast 65 or formed with a partition 7 extending obliquely across it from a point above the inlet 16 to a point below the outlet 16^a, and below this partition the casing is continued downward some distance so as to form a distinct 70 sediment chamber 2 of large size and preferably of cylindrical contour. This chamber is closed at its lower end by a closure; or, as illustrated, it may be extended further downward so as to increase its capacity and the 75 lower end of the extension closed by a suitable cap. Above the partition 7 is formed another and relatively shorter chamber in which is located the screen described below. If the latter be constructed as herein shown 80 and described, the partition is provided with a shouldered opening 19 concentric with the axis of the casing but of smaller diameter than its interior. Depending from the partition is a baffle plate 8 curving downward 85 from the upper side of this opening, over and around the inlet 16, with its lower edge extending below the lower line of the inlet and standing substantially on the axis of the casing so that the inflowing liquid will be directed 90 downward into the sediment chamber 2.

The strainer proper comprises a screen 4 which is of inverted cup shape with its lower end cut off oblique as seen in Fig. 3, and 95 perforations through the side wall and the top 4^a of this screen of such size and number as to aggregate a passageway having from two to three times the capacity of the pipe connections. It will be observed that the 100 larger side wall of this screen is presented toward the outlet 16^a, although there is an annular space within the body entirely around its side wall and an additional space between its top and the cap 15; and this arrangement affords the greatest capacity for 105 the passage of liquid into and through the screen, and thereby prevents the strainer

from choking even when the liquid is forced through by or under pressure. The open lower end of the screen rests upon the shoulder of the opening 19 and is preferably strengthened by a ring 17 secured thereto as by soldering or otherwise, and its upper corner is also preferably strengthened by a ring 12.

The numeral 5 designates a spider whose 10 arms may be attached rigidly to the ring 12 or notched at their tips so as to removably engage it, and the hub of this spider has a socket 21 adapted to be engaged by a set screw 6 which takes through the cap 15 and 15 may be protected by a plug 3. Obviously the screen and its parts are inserted from above by removing the cap 15, and when in place the set screw holds all parts firmly in position and resists their dislocation while 20 the device is in action.

The liquid entering the inlet 16 strikes the baffle plate 8 and is deflected downward toward and along the axis of the sediment chamber 2. Filling the latter, it rises behind the 25 baffle plate, through the opening 19, and into the screen 4. If the volume of liquid is small and the pressure light, it will pass through the lower portion of the longest wall of the screen as indicated by the group of four 30 arrows. As the volume and pressure increase the liquid will rise higher within the screen and more of the perforations will come into play. With still greater volume and pressure the liquid will rise still further, 35 and eventually all the perforations in the side wall and in the top of the screen will come into play, as indicated by all the arrows, yet there is no possible way for any liquid to reach the outlet 16^a without passing 40 through some portion of the screen. Meanwhile any heavy particles of matter that may flow in at 16 will be deflected by the baffle plate and will sink by gravity in and remain at the bottom of the sediment 45 chamber 2, and other particles possibly lighter or which may be carried by the current up into the screen will also eventually settle and lodge in said chamber. The result is that the sediment strained from the 50 liquid will accumulate in the chamber, and if the latter is voided frequently it can be done by removing the plug 10 when the pressure of the liquid will blow out the accumulated sediment. If the chamber is not voided 55 frequently or the liquid is particularly foul or the particles of sediment large, it may be necessary to remove the entire cap 9. In some instances where this strainer will not receive attention save at long periods, it 60 may be desirable to employ an extension like that lettered 15^a or one of greater length so as to materially increase the capacity of the sediment chamber. From time to time the interior of said chamber can be cleaned 65 by first cutting off the inlet and then entirely

removing the lower closure so as to gain access to the interior. Similarly the upper portion of the casing can be cleaned by removing the upper closure and withdrawing the screen. All parts are preferably of metal, 70 although the exact material and the sizes and proportions are unimportant to the successful operation of the device. Wide departure from the described and illustrated means of connecting the pipes 14 or detach- 75 ing the closures may be made at the pleasure of the manufacturer.

What is claimed as new is:

1. A liquid strainer comprising an upright casing having a cross passage communicating with the inlet and outlet and interrupted by a straight oblique partition provided with a shouldered opening concentric with the axis of the casing, said partition forming a distinct sediment chamber in the casing beneath it and a smaller chamber above it; 80 combined with a screen of inverted cup shape cut off oblique at its lower end and with its body engaging the shoulder in said opening, its side and top walls remote from the interior of said casing and its longer side wall adjacent the outlet, a reinforcing ring around the upper corner of the screen, a spider whose arms engage said ring and whose hub has a socket, closures for the upper and lower ends of the casing, a set screw through the upper closure engaging said socket, and a baffle plate projecting from the higher edge of said partition inward and curving downward over the inlet to a point 90 substantially at the center of the casing and below the lowest line of said cross passage. 95

2. A liquid strainer comprising an upright casing having a cross passage communicating with the inlet and outlet and interrupted by a straight oblique partition provided with a shouldered opening concentric with the axis of the casing, said partition forming a distinct sediment chamber in the casing beneath it and a smaller chamber above it; 105 combined with a screen of inverted cup shape cut off oblique at its lower end and with its body engaging the shoulder in said opening, its side and top walls remote from the interior of said casing and its longer side 115 wall adjacent the outlet, a reinforcing ring around the upper corner of the screen, a spider whose arms engage said ring and whose hub has a socket, closures for the upper and lower ends of the casing, and a set 120 screw through the upper closure engaging said socket.

3. A liquid strainer comprising an upright casing having a cross passage communicating with the inlet and outlet and interrupted by a straight oblique partition provided with a shouldered opening concentric with the axis of the casing, said partition forming a distinct sediment chamber in the casing beneath it and a smaller chamber above it; 125 130

combined with a screen of inverted cup shape cut off oblique at its lower end and with its body engaging the shoulder in said opening and remote from the interior of said casing and its longer side wall adjacent the outlet, closures for the upper and lower ends of the casing, and a baffle plate projecting from the higher edge of said partition inward and curving downward over the inlet to a point substantially at the center of the casing and below the lowest line of said cross passage.

1. A liquid strainer comprising an upright casing having a cross passage communicating with the inlet and outlet and interrupted by a straight oblique partition provided with a shouldered opening concentric with the axis of the casing, said partition forming a distinct sediment chamber in the casing beneath it and a smaller chamber above it; combined with a screen of inverted cup shape cut off oblique at its lower end with its body engaging the shoulder in said opening and remote from the interior of said casing and its longer side wall adjacent the outlet, and closures for the upper and lower ends of the casing.

5. A liquid strainer comprising an upright casing having a cross passage communicating with the inlet and outlet and interrupted by a straight oblique partition provided with an opening concentric with the axis of the casing, said partition forming a distinct sediment chamber in the casing beneath it; combined with a screen of inverted cup shape cut off oblique at its lower end with its body engaging said opening, its side and top walls remote from the interior of said casing and its longer side wall adjacent the outlet, a reinforcing ring around the upper corner of the screen, a spider whose arms engage said ring and whose hub has a socket, closures for the upper and lower ends of the casing, a set screw through the upper closure engaging said socket, and a baffle plate projecting from the higher edge of said partition inward and curving downward over the inlet to a point substantially at the center of the casing and below the lowest line of said cross passage.

6. A liquid strainer comprising an upright casing having a cross passage communicating with the inlet and outlet and interrupted by a straight oblique partition with an opening concentric with the axis of the casing, said partition forming a distinct sediment chamber in the casing beneath it; combined with a screen of inverted cup shape cut off oblique at its lower end and with its body engaging said opening and remote from the interior of said casing and its longer side wall adjacent the outlet, closures for the upper and lower ends of the casing, and a baffle plate projecting from the higher edge of said partition inward and curving downward over

the inlet to a point substantially at the center of the casing and below the lowest line of said cross passage.

7. A liquid strainer comprising an upright casing having a cross passage communicating with the inlet and outlet and interrupted by a straight oblique partition provided with an opening concentric with the axis of the casing, said partition forming a distinct sediment chamber in the casing beneath it; combined with a screen of inverted cup shape cut off oblique at its lower end and with its body engaging said opening and remote from the interior of said casing and its longer side wall adjacent the outlet, closures for the upper and lower ends of the casing, and a baffle plate projecting from the higher edge of said partition inward and downward over the inlet to a point substantially at the center of the casing.

8. A liquid strainer comprising an upright casing having a cross passage communicating with the inlet and outlet and interrupted by a straight oblique partition provided with an opening concentric with the axis of the casing, said partition forming a distinct sediment chamber in the casing beneath it; combined with a screen of inverted cup shape cut off oblique at its lower end and with its body engaging said opening and remote from the interior of said casing and its longer side wall adjacent the outlet, closures for the upper and lower ends of the casing, and a baffle plate projecting from the higher edge of said partition inward and downward over the inlet to a point below the lowest line of said cross passage.

9. A liquid strainer comprising an upright casing having a cross passage communicating with the inlet and outlet and interrupted by a partition provided with a shouldered opening concentric with the axis of the casing, said partition forming a distinct sediment chamber in the casing beneath it and a smaller chamber above it; combined with a screen of inverted cup shape its lower end engaging the shoulder in said opening and its body being remote from the interior of said casing, closures for the upper and lower ends of the casing, and a baffle plate projecting from the higher edge of said partition inward and curving downward over the inlet to a point substantially at the center of the casing and below the lowest line of said cross passage.

10. A liquid strainer comprising an upright casing having a cross passage communicating with the inlet and outlet and interrupted by a partition provided with an opening concentric with the axis of the casing, said partition forming a distinct sediment chamber in the casing beneath it; combined with a screen of inverted cup shape its lower end engaging said opening and its body being remote from the interior of the casing,

closures for the upper and lower ends of the
casing, and a baffle plate projecting from the
higher edge of said partition inward and
curving downward over the inlet to a point
substantially at the center of the casing and
below the lowest line of said cross passage.

In testimony whereof I have hereunto

subscribed my signature this the 2nd day of
November, A. D. 1907.

HENRY MUELLER.
